PRODUCTION OF SULPHONATES OF
TERTIARY ALCOHOLS

Anton Hintermaier, Dusseldorf, Germany, assignor to the firm Henkel & Cie, Gesellschaft mit beschränkter Haftung, Dusseldorf, Germany

No Drawing. Application April 28, 1934, Serial No. 722,966. In Germany August 2, 1933

10 Claims. (Cl. 260—159)

Sulphonation products of tertiary alcohols are already known, the tertiary alcohols being first converted into olefines, which are then converted into sulphonation products by treatment with sulphuric acid of varying water-content. The resulting acid sulphuric esters are very unstable and to some extent are so unstable that they are hydrolyzed even by the moisture of the air. Owing precisely to their instability, such products cannot be employed in industry or in the household.

This invention relates to a process for sulphonating tertiary alcohols, which are substituted at the tertiary carbon atom with at least one long chain higher aliphatic and/or at least one hydroaromatic radical, or derivatives of such alcohols, in such a manner as to form true sulphonic acids which are not only water-soluble but are also stable to hydrolysis. The process comprises treating the said tertiary alcohols, or their derivatives, with strongly sulphonating and dehydrating agents. Sulphonating agents within the meaning of the invention comprise sulphonating agents which have both a sulphonating a dehydrating action, such as oleum and chlorosulphonic acid, halogen sulphonic acids, and also mixtures of sulphonating substances and dehydrating substances. Among such dehydrating substances may be mentioned for example: Simple or mixed acid anhydrides of inorganic or organic acids, such as for example, acetic anhydride, acid halides, for example acetyl chloride, phosphorus halides, and also dehydration products of hydroxyl-containing acids of the type of pyro or meta acids or their salts, furthermore, salts having a dehydrating action and the like. Mixtures of concentrated sulphuric acid and acetic anhydride, or of sulphuric acid containing SO_3 and acetic acid, are suitable. If desired, the sulphonation can be carried out with the further addition of solvents or sulphonation accelerators. Among the substances which come into consideration as starting materials are the tertiary alcohols, which are obtainable from glycerides or alkyl esters of higher saturated or unsaturated fatty acids, or of naphthenic acids, resinic acids and the like, by the action of magnesium halogen alkyls.

The sulphonation of the tertiary alcohols may also be carried out in two stages, the tertiary alcohols being first treated with dehydrating agents, and the dehydration products being thereupon sulphonated. This may be carried out for instance by adding to the alcohols first of all

the herein-mentioned dehydrating agents and then, after reaction has taken place, the sulphonating agents.

The high-molecular true sulphonic acids obtained according to the invention are remarkable among other things for their considerable wetting and emulsifying action, and are therefore excellent for use as capillary-active or surface-active agents, more particularly as wetting, washing, cleansing, emulsifying and dispersing agents.

Preferably, the sulphonic acids of unsaturated tertiary carbinols, and of mixtures of homologous compounds have been found to be suitable.

More particularly, the salts of the said sulphonic acids, for example the sodium, potassium or triethanolamine salts or the salts of other amines may be employed for the purposes specified.

It has been found that the said compounds may be employed advantageously wherever the capillary-active properties of liquids, more particularly aqueous liquids, are to be enhanced. Due to their capillary-active properties, the compounds may be employed for example for foam-production, emulsifying, dispersing, impregnating, peptizing, stabilizing, levelling, distributing, dissolving and the like in many different industries. They may be employed for example as assistants in the leather, fur and more particularly in the textile industry in many different working processes.

The said substances exhibit their activity also in admixture with other substances; thus, apart from these substances, other additions, for example, alkaline agents, per-compounds, superfatting agents and the like may be added to the treatment baths. They may be employed in acid, neutral and alkaline liquids and baths, and also in baths containing electrolytes, lime, magnesia or other substances which render water hard. They may be employed either alone or in admixture with other wetting, washing, cleansing, emulsifying and dispersing agents; furthermore, there may be added to the said compounds, for example per-compounds, such as perborates, persulphates and percarbonates, or alkaline agents such as soda, trisodium phosphate, water glass and borax, or neutral agents, such as sodium sulphate, or even acid agents, such as acid sodium sulphate.

Also, the compounds may be employed in admixture with solvents, such as organic hydrocarbons, alcohols and the like or in admixture with enzymes, such as urease and pancreatin.

The agents manufactured with a content of

the new compounds may be put on the market in the solid form, for example in the form of powders, flakes, lumps or shreds or the like, and also for household purposes. They may, however, be put on the market already dissolved in liquids, or in the form of pastes and creams, such as for example in cosmetic preparations, polishing agents, soap creams and the like.

The liquids manufactured with the said agents may be employed either in the hot or cold state.

Example 1

Into 50 parts of undecyl diethyl carbinol, which have been dissolved in 50 parts of acetic anhydride, are introduced in drops 50 parts of concentrated sulphuric acid while stirring and cooling by ice. The sulphonation is completed by heating to room temperature. The resulting viscous solution is poured upon ice and the mass is then mixed with 100 parts of butanol. The aqueous layer, which contains the bulk of the acid, is separated. The butyl alcohol solution of the sulphonation product is neutralized by means of sodium bicarbonate. After separating the resulting precipitate, the filtrate is evaporated down in a vacuum.

Example 2

For the purpose of the better levelling of acid wool dyes, 0.2 to 0.5 per cent of the sodium salt of the sulphonation product of a mixture of higher carbinols, which correspond to the soya fatty acids and are substituted at the carbinol carbon atom by 2 ethyl groups, is added to the dyeing bath. The said sulphonation product is remarkable for its excellent wetting power. It is stable to lime and acid. The effect occurs in the treatment both of piece goods and of goods in the hank.

Example 3

In dyeing artificial silk materials, which exhibit a tendency to unevenness, for example in dyeing stockings on apparatus, about 0.4 to 0.6 per cent. of the sodium salt of the sulphonation product of a mixture of higher carbinols, which correspond to whale oil fatty acids and are substituted at the carbinol carbon atom by 2 methyl groups, is added to the bath. The goods are wetted right through and dyed evenly.

Example 4

In bucking, 0.1 to 0.3 per cent of the sodium salt of the sulphonation product of a mixture of higher carbinols, which correspond to the soya oil fatty acids and are substituted at the carbinol carbon atom by 2 methyl groups, is added to the bath. Due to the stability of the sulphonation product to lime, lime deposits are prevented. A very even fabric is obtained.

The product may also be employed with equal success as an addition to mercerizing lyes.

Example 5

The sodium salt of the sulphonation product of a mixture of higher carbinols, which correspond to linseed oil fatty acids and are substituted at the carbinol carbon atom by 2 ethyl groups, is added to an alkaline cleansing agent in order to enhance the wetting power. The agent may be employed, more particularly in automatic machines, where it is important to prevent the formation of foam as far as possible but where an excellent cleansing and wet-

ting power is desirable. It is remarkable for its stability to lime and acid, and its ready solubility.

Example 6

The sodium salt of the sulphonation product of a mixture of higher carbinols, which correspond to the sperm oil fatty acids and are substituted at the carbinol carbon atom by 2 methyl groups, may be employed very successfully for the manufacture of sizes and finishes. Its aqueous solutions exhibit a remarkable wetting power with regard to textiles, such as cotton and wool. Owing to its pronounced stability to lime, the sulphonation product may also be employed with very hard water.

Example 7

The triethanolamine salt of the sulphonation product of a mixture of higher carbinols, which correspond to the coconut oil fatty acids and are substituted at the carbinol carbon atom by 2 methyl groups, is excellent for use for the manufacture of emulsions, which can be used as spinning lubricants, floor polishing compositions and the like.

I claim:

1. The process for the manufacture of high-molecular true sulphonic acid products, which comprises treating with strongly sulphonating and dehydrating agents mixtures of homologous tertiary alcohols, which are produced from glycerides of acids having higher aliphatic radicals, by the action of magnesium halogen alkyls.

2. The process described in claim 1, wherein said acid is an unsaturated fatty acid.

3. The process for the manufacture of high-molecular true sulphonic acid products, wherein a mixture of homologous tertiary alcohols, which are produced from glycerides of acids having higher aliphatic radicals, by the action of magnesium halogen alkyls, is treated first with a dehydrating agent and then with a sulphonating agent.

4. The process for the manufacture of high-molecular true sulphonic acid products, wherein a mixture of homologous tertiary alcohols, which are produced from glycerides of acids having higher aliphatic radicals, by the action of magnesium halogen alkyls, is treated first with dehydrating agents and then with sulphonating and dehydrating agents.

5. The process for the manufacture of high-molecular true sulphonic acid products which comprises treating a mixture of homologous tertiary alcohols, which are produced from glycerides of acids having higher aliphatic radicals, by the action of magnesium halogen alkyls, with sulphonating and dehydrating agents in the presence of solvents.

6. The process for the manufacture of high-molecular true sulphonic acid products which comprises treating a mixture of homologous tertiary alcohols, which are produced from glycerides of acids having higher aliphatic radicals, by the action of magnesium halogen alkyls, with sulphonating and dehydrating agents in the presence of sulphonation accelerators.

7. The process for the manufacture of high-molecular true sulphonic acid products which comprises treating a mixture of homologous tertiary alcohols, which are produced from glycerides of acids having higher aliphatic radicals, by the action of magnesium halogen alkyls, with dehy-

drating agents and with agents having both a dehydrating and sulphonating action.

8. A new product of manufacture consisting of a high-molecular true sulphonic acid product obtained by treating with strongly sulphonating and dehydrating agents a mixture of homologous tertiary alcohols, which are produced from glycerides of acids having higher aliphatic radicals, by the action of magnesium halogen alkyls.

10 9. A new product of manufacture consisting of a water-soluble salt of a high-molecular true

sulphonic acid product obtained by treating with strongly sulphonating and dehydrating agents a mixture of homologous tertiary alcohols, which are produced from glycerides of acids having higher aliphatic radicals, by the action of magnesium halogen alkyls.

10. The new product of manufacture described in claim 9, wherein said acid is an unsaturated fatty acid.

ANTON HINTERMAIER. 10
